(57) **CLAIM**

The ornamental design for a beverage insulator with communications indicia, as shown and described.

DESCRIPTION

FIG. 1 is a perspective view of a first embodiment of the beverage insulator;

FIG. 2 is a second perspective view of the first embodiment of the beverage insulator;

FIG. 3 is a top view of the first embodiment of the beverage insulator;

FIG. 4 is a side view of the first embodiment of the beverage insulator;

FIG. 5 is a bottom view of the first embodiment of the beverage insulator;

FIG. 6 is a second side view of the first embodiment of the beverage insulator;

FIG. 7 is a perspective view of a second embodiment of the beverage insulator;

FIG. 8 is a perspective view of a third embodiment of the beverage insulator (the views not shown for this Figure are not being claimed);

FIG. 9 is a perspective view of a fourth embodiment of the beverage insulator (the views not shown for this Figure are not being claimed);

FIG. 10 is a top view of the fourth embodiment of the beverage insulator;

FIG. 11 is a side view of the fourth embodiment of the beverage insulator;

FIG. 12 is a bottom view of the fourth embodiment of the beverage insulator; and,

FIG. 13 is a second side view of the fourth embodiment of the beverage insulator.

The broken lines are for illustrative purposes only and form no part of the claimed design.
